UNITED STATES PATENT OFFICE.

JAMES H. THOMPSON, OF TRENTON, NEW JERSEY, ASSIGNOR TO HUSSONG DYEING MACHINE COMPANY, OF GROVEVILLE, NEW JERSEY, A CORPORATION OF NEW JERSEY.

DYEING MACHINE.

Original application filed February 23, 1918, Serial No. 263,856. Divided and this application filed August 20, 1921. Serial No. 493,852.

To all whom it may concern:

Be it known that I, JAMES H. THOMPSON, a citizen of the United States, residing in Trenton, Mercer County, New Jersey, have 5 invented certain Improvements in Dyeing Machines, of which the following is a specification.

My invention relates to certain improvements in dyeing machines of the type in 10 which the hanks of yarn are suspended in a vat and in which a circulating means is located at one end of the vat so that the liquor will be circulated through the vat in either direction.

15 This application is a division of the application for patent filed by me on the 23rd day of February, 1918, Serial No. 263,856, which resulted in a patent granted on the 25th day of October, 1921, No. 1,395,165.

20 The object of my invention is to improve the construction of the means for suspending the hanks of yarn in the vat so as to prevent the straining of the sticks and to provide means whereby the rods, which are 25 located at the top and bottom of the vat, can be readily removed and replaced when breakage occurs.

In the accompanying drawings:

20 Fig. 1 is a longitudinal sectional view of a dyeing machine illustrating my invention;

Fig. 2 is a sectional view on the line 2—2, Fig. 1;

Fig. 3 is a sectional view, similar to Fig. 2, illustrating the method of removing the 35 sticks; and

Fig. 4 is a sectional view on the line 4—4, Fig. 1.

Referring to the drawings, 1 is the vat. At one end of the vat is a circulating device 40 consisting of a power driven shaft 2 having a propeller 3. This propeller is located in a circulating passage 4 separated from the main body 5 of the vat by a partition 6, which stops short of the top and bottom of 45 the vat so that the liquor can circulate through the body of the vat and the circulating passages.

The propeller is driven by power mechanism applied to the shaft 7 mounted on a 50 suitable frame 8. It will be understood that other circulating means may be used without departing from the essential features of the invention.

In the bottom of the vat is a grating con-

sisting of side bars 9 and cross bars 10. The 55 side bars are made in halves and the sockets of the cross bars are formed in these side bars, one-half in the lower section and the other half in the upper section. The cross bars do not extend through the side bars, but 60 merely rest in the sockets so that when the bolts 11 are in position they secure the two parts of the side bars together and clamp the ends of the cross bars, as shown in Fig. 4. The cross bars are preferably in a line with 65 the lower edge of the partition 6 and form a bottom channel through which the liquor can flow freely to and from the circulating passage 4.

12 is a supporting frame for the hanks of 70 yarn. This frame consists, in the present instance, of two longitudinal side beams 13 and a central beam 14. These beams are connected together by cross beams 15 provided with eyes 16, which are engaged by the 75 lifting tackle when it is desired to lift the frame, with the hanks of yarn thereon, into or out of position in the vat. There are a series of perforations 17, which extend through the side beams 13 and a series of 80 perforations 18 in the central beam 14. These latter perforations do not extend through the beam, Fig. 3.

The yarn sticks 19 are located in these 85 perforations, one series of sticks being on one side of the center beam and the other series being on the opposite side. By providing a central beam, as shown, the sticks need not be so long as usual, and, consequently, they do not sag and become accidentally detached from the supporting frame, and are not warped out of position. Furthermore, they carry a fewer number of sticks than heretofore and are more readily handled by the operator than when long 95 sticks are used.

Directly above the yarn carrying sticks is a grating, similar to the one at the bottom of the vat, consisting of a series of wooden bars 20. These bars are spaced a given distance apart and are clamped under the beams 13 and 14 by bars 21. These cross bars are short, one set extending on one side of the central beam and the other on the opposite side thereof. They do not extend through the beams, but merely rest in the sockets formed in the beams, and the bars so that when it is desired to replace one of the bars,

on account of breakage, all that is necessary is to loosen one of the side clamping bars to remove the broken cross bar and to place a new bar in its place.

5 Carried by the supporting frame is a cover 22 for closing the vat during the process of dyeing. This cover has two hinged portions, one at each side, so that access can be readily had to the interior of the vat to inspect the circulation. The remainder of the cover is made of a series of sections which can be removed, if found desirable.

10 The operation is as follows: The dye liquor is placed in the vat and the circulating means is set in motion so as to circulate the liquor in the vat. Steam is added through the pipes 23 in order to bring the liquor to the proper temperature. The particular color of dye is also 15 added until it is thoroughly impregnated with the dye liquor. The hanks of yarn are then placed on the sticks and the sticks are located in the frame, which is supported from an overhead trolley beam and when the 20 liquor is in the proper condition to die the material, the yarn frame is swung over the vat and lowered into it so that the hanks of 25 yarn will be submerged in the liquor.

On each inner wall of the vat are located 30 bars 24, which come in close contact with the side beams of the supporting frame for the 35 yarn and close the space between the side beams and the side of the vat in order to prevent the circulation of the dye liquor at this point and to insure all of the liquor being circulated through the hanks of yarn. The 40 circulating means can be reversed so as to

circulate the dye liquor in either direction through the yarn. One form of circulating means is fully disclosed in Patents No. 40 661,343, Nov. 6, 1900, and No. 1,395,165, October 25, 1921.

I claim:

1. The combination in a dyeing machine, 45 of a vat; means for circulating the dye liquor therein; a supporting frame for the yarn consisting of three longitudinal beams, two of the beams being perforated for the sticks on which the yarn is suspended, the central beam having recesses at each side for the 50 yarn sticks; and two series of sticks, one located at one side of the center beam and the other located at the opposite side thereof.

2. The combination in a dyeing machine, 55 of a vat; means for circulating dye liquor in the vat; a supporting frame consisting of two longitudinal beams and sticks on which the yarn is suspended, said frame being located in the upper portion of the vat; and 60 means, on the inner walls of the vat, for preventing the circulation of liquor between the side beams of the supporting frame and the walls of the vat.

3. The combination of a vat; means for 65 circulating liquor in the vat; and a yarn supporting frame mounted in the vat and having its longitudinal members comparatively close to the side walls of the vat, said vat having longitudinal bars extending under 70 the sides of the frame so as to prevent the circulation of liquor between the supporting frame and the side of the vat.

JAMES H. THOMPSON.
